(57) **CLAIM**

The ornamental design for a carrying case for an optical fiber fusion splicer, as shown and described.

DESCRIPTION

FIG. 1 is a front view of a first embodiment of a carrying case for an optical fiber fusion splicer.

FIG. 2 is a rear view of the first embodiment of the carrying case for an optical fiber fusion splicer.

FIG. 3 is a top plan view of the first embodiment of the carrying case for an optical fiber fusion splicer.

FIG. 4 is a bottom view of the first embodiment of the carrying case for an optical fiber fusion splicer.

FIG. 5 is a right side view of the first embodiment of the carrying case for an optical fiber fusion splicer.

FIG. 6 is a left side view of the first embodiment of the carrying case for an optical fiber fusion splicer.

FIG. 7 is a perspective view of the first embodiment of the carrying case for an optical fiber fusion splicer.

FIG. 8 is a top plan view with the lid open of the first embodiment of the carrying case for an optical fiber fusion splicer.

FIG. 9 is a perspective view with the lid open of the first embodiment of the carrying case for an optical fiber fusion splicer.

FIG. 10 is a reference view of the first embodiment of the carrying case for an optical fiber fusion splicer; and,

FIG. 11 is another reference view of the first embodiment of the carrying case for an optical fiber fusion splicer.

The broken lines showing of the handles, inside of the carrying case, and other features are included for the purpose of illustrating environmental structure and forms no part of the claimed design.
